UNITED STATES PATENT OFFICE.

CHARLES C. TOMKINSON, OF PLAINFIELD, NEW JERSEY, ASSIGNOR TO GEORGE H. FROTHINGHAM COMPANY, OF NEW YORK, N. Y., A CORPORATION OF NEW YORK.

DOOR-CONTROL MECHANISM.

1,276,996.

Specification of Letters Patent. Patented Aug. 27, 1918.

Application filed May 8, 1916. Serial No. 95,286.

To all whom it may concern:

Be it known that I, CHARLES C. TOMKINSON, a citizen of the United States, and a resident of Plainfield, Union county, and 5 State of New Jersey, have invented certain new and useful Improvements in Door-Control Mechanism, of which the following is a specification, reference being had to the accompanying drawings, forming a part 10 thereof.

My invention relates to doors and has special reference to such as have their lower corners raised vertically and of which the upper corners are adapted to swing away 15 from the door opening on tracks or guideways which are horizontal or at a suitable angle to the plane of the door opening.

One object of my invention is to provide 20 means for forcing the respective sides of the door at the points of support to move at the same speed, or, in other words, to maintain a parallel relation between the pivotal axis of the door and the plane of the door opening at all times.

Other objects and advantages of my invention will be set forth hereinafter, and in order that my invention may be thoroughly understood I will now proceed to describe the same in the following specification and 25 then point out the novel features thereof in appended claims.

Referring to the drawings:

Figure 1 is a partially diagrammatic sectional elevation of a door arranged and constructed in accordance with my invention. 30

Fig. 2 is a partial plan view of the door in its open position with the guard rail removed.

A modified arrangement is shown in Fig. 40 3 which corresponds to Fig. 1.

Still other modifications are shown in Figs. 4 and 5 which are plan views showing the doors in their open position, their closed positions being indicated by broken 45 lines.

Referring to Figs. 1 and 2,—10 designates a door having affixed to it near its upper corners a pair of brackets 11 which constitute bearings for a transverse shaft 12. 50 Secured to the shaft at its respective ends are a pair of toothed or spiked wheels 13 which are adapted to coöperate with stationary guide rails 14. The rails may be perforated as shown in Fig. 2, or may have 55 the form of racks, or otherwise be adapted

to coöperate with the wheels and prevent the slipping of the wheels 13 thereon.

Since the wheels are both secured to the same shaft and are substantially alike, they obviously travel at the same speed and the 60 top of the door is maintained parallel to the plane of the door opening at all times.

In order to prevent the wheels from being accidentally lifted off the rails 14, a 65 guard rail 15 is mounted directly above and parallel to each of the rails 14, preferably over the hubs 13^a of the wheels 13, sufficient space being allowed to permit the free movement of the wheel.

Rollers 16 are preferably located near the 70 bottom of the door at its respective edges and stationary guide members 17 are mounted on the door posts to coöperate with the rollers.

Hoisting chains 18 extend upwardly 75 from the bottom of the door over sheaves 19 to a counterweight 20.

The door is preferably provided with a handle 21 located near its bottom edge which may be grasped to swing the door 80 open and closed.

In the arrangement of Fig. 3, a pair of smooth rimmed wheels 25 are substituted for the toothed wheels 13 and run on smooth rails 26. The rollers or wheels 25 may be 85 mounted directly on the brackets 11 since it is unnecessary that the two wheels be tied together as in the previous arrangement. Mounted slightly beyond the outer limit of movement for the top of the door is 90 a shaft 27 substantially equal in length to the width of the door and having secured to its respective ends sprocket wheels or pocket sheaves 28. These wheels or sheaves are connected by endless chains 29 to idler 95 sheaves 30 which are mounted on brackets 31, above the door opening with their common axis substantially in the plane of the same.

The chains 29 are connected to the 100 brackets 11 and hence the edges of the door 10 to which the brackets are secured are forced to move at the same speed in opening or closing. This is evident from the fact that the chains cannot slip on the pulleys 105 28 and the pulleys 28 are both secured to the same shaft 27.

The arrangement of Fig. 4 comprises track rails 26 and wheels 25 as in Fig. 3, but instead of the sprocket wheels or pocket 110

sheaves there are a plurality of idler pulleys 32 to 37 inclusive. The pulleys 32 and 37 are mounted on stationary brackets 38 and 39 and are located near the outer ends 5 of the track rails 26. The pulleys 33 and 34 are grouped near the inner end of one of the rails and the pulleys 35 and 36 near the inner end of the other rail.

A chain or cord is secured by a fastener 10 40 to the top of the door near one corner and extends successively around the pulleys 32, 33, 35, 37, 36 and 34, and back to the same point. It is also secured between the pulleys 35 and 37 by a fastener 41 to the 15 top of the door near its opposite edge. As the fastener 40 moves away from the plane of the door opening, it pulls on the chain or cord as indicated by the arrow 42, an equal movement in the same direction being necessarily exerted upon the door at the fastener 41. Conversely, any pull exerted on the fastener 41 acts through the rope in the direction of the arrow 43 and exerts a pull on the fastener 40. Thus the movements 20 are necessarily uniform on both edges of the door and the pivotal axis of the door is maintained in parallelism to the plane of the door opening.

By any of the aforesaid means the possibility of binding or sticking at the door edges is avoided, the operation is improved, and manipulation of the door is facilitated.

In Fig. 5 parallelism is maintained by a lazy tongs structure comprising a pair of links 44 and 45 which are connected together at 46 and a pair of links 47 and 48 which are connected together at 48^a and to the first pair at 49.

The inner end of the link 44 is connected 40 to a stationary pivot 50 disposed in a recess 51 above the door opening and the outer end of the link 45 is connected to the door 45 at the top by a hinge and pivot connection 52.

The inner end of the link 47 is pivoted to a sliding block 53 which is adapted to move 55 within the recess 51 in a track 54, in a line parallel to the plane of the door opening. The outer end of the link 48 is pivoted to a block 55 which slides on a short rail or strip 56 secured to the top of the door.

The arrangement is such as to keep the top of the door always parallel to the plane of the door opening.

When the door is shut the lazy tongs fold 55 into the position shown in broken lines in Fig. 5 and when the door is open they are extended as shown in full lines.

Other modifications of my invention will suggest themselves to those skilled in this art, and I intend that only such limitations be imposed as are indicated in appended claims.

What I claim is:

1. The combination with a door having 65 its lower corners guided to move in a plane parallel with the door opening and with its upper corners adapted to swing away from the door opening at the top, hoisting mechanism connected to the door, stationary 70 guide means in the plane of the door opening for the lower corners of the door, track rails extending in the direction of movement of the top of the door and located near its respective edges, rollers secured to the 75 door on a common axis and co-operating with said rails, and means for causing the respective upper corners of the door to travel outwardly at the same speed whereby the axis of said rollers is maintained in parallel relation with the lower edges of the door during the upward movement of said corners.

2. The combination with a door having 80 its lower corners adapted to be moved in a plane parallel with the door opening and with its upper corners adapted to swing away from the plane of the door opening at the top, of guide rails extending at an angle to the plane of the door opening, rollers on the door adapted to co-operate with 85 the track rails, and a pair of endless chains adjacent to the guide rails and connected to opposite edges of the door, and means for interconnecting the chains to insure their concurrent movement.

3. The combination with a door having 90 its lower corners adapted to be moved in a plane parallel with the door opening and with its upper corners adapted to swing away from the plane of the door opening at the top, of guide rails extending at an angle to the plane of the door opening, rollers on the door adapted to co-operate with the track rails, a pair of endless chains adjacent to the guide rails, a pocket sheave for 95 each chain, and an interconnecting shaft to which the pocket sheaves are secured, whereby the pivotal axis of the door is maintained in parallel relation to the plane of the door opening.

In witness whereof I have hereunto set my hand this 2nd day of May, 1916.

CHARLES C. TOMKINSON.

Witness:

E. B. Moore.
